APPARATUS FOR TREATING EXHAUST
GASES

Max H. Wolff, Chicago, Ill.

Application August 3, 1931, Serial No. 554,768

5 Claims. (Cl. 261—104)

This invention relates to apparatus for treating the products of combustion emanating from a combustion chamber, and is particularly adapted for use in conjunction with internal combustion engines having mufflers operatively related to the exhaust manifold thereof.

One object of the present invention is to provide a device or apparatus used in eliminating or modifying the obnoxious character of the products of combustion resulting from incomplete combustion of fuel in the combustion chambers.

Another object of the invention is to provide a device whereby the products of combustion may be combined or mixed with air in a chamber or compartment before being discharged from the device.

Another object of the invention is to provide means for supplying a neutralizing and deodorizing agent to said compartment in a manner to be taken up by the air and commingled with the gases of combustion.

A further object of the invention is to provide a device which is simple in construction, economical to manufacture, and which may be readily attached to mufflers of motor vehicles adjacent the discharge end thereof.

A still further object of the invention is to improve devices of the character described in sundry details hereinafter referred to and particularly pointed out in the appended claims.

One embodiment of the present invention is shown for illustrative purposes in the accompanying drawing, in which

Fig. 1 is a central longitudinal sectional elevation view of my improved apparatus illustrating its application to an ordinary type of muffler used on motor vehicles, and taken substantially as indicated by the line 1—1 in Figs. 2 and 3;

Fig. 2 is an end view of the structure shown in Fig. 1 as viewed from the left end thereof; and

Fig. 3 is an enlarged transverse sectional elevation taken substantially as indicated by the line 3—3 of Fig. 1.

In the embodiment shown in the drawing, a muffler of ordinary type, indicated as a whole by the numeral 5 is provided, adjacent its forward end, with a pipe 6 connected to a conduit 7 adapted to communicate with the exhaust manifold of an internal combustion engine, such as is commonly used in motor vehicles, while the opposite or rear end of the muffler 5 is provided with an exhaust pipe 8 through which the gases of combustion are discharged after passing through the muffler. The illustrative embodiment of the present invention comprises a tubular member 9

extending beyond the discharge end of the exhaust pipe 8 and secured thereto by screws 10, the tubular member 9 having a somewhat greater inside diameter than the outside diameter of the exhaust pipe 8, and being spaced therefrom by means of a spacer block 11 in a manner to provide an air passage 12 between the exhaust pipe 8 and the inner surface of the tubular member 9.

Suitably supported on the muffler 5 is a housing indicated as a whole by the numeral 13 comprising a forward portion 14 extending longitudinally a substantial distance along the lower side of the muffler 5 and spaced therefrom as indicated at 15, the portion 14 having its longitudinally extending upper edge portions 16 rigidly secured to the sides of the muffler casing 17 by welding or other suitable means, while the forward annular edge 18 of the portion 14 is preferably flared outwardly to receive a substantial volume of air for passage through the space 15 between the portion 14 and the lower side of the muffler casing 17.

The housing 13 also comprising a rearwardly extending preferably tapered portion indicated as a whole by the numeral 19 adapted to surround the exhaust pipe 8 and the tubular member 9, the portion 19 being provided, in the present instance, with an inclined portion 20 preferably adjacent its lower side and adapted to extend beyond the discharge end of the tubular member 9.

The portion 20 is provided with a preferably elongated aperture 21 adapted to receive a pad 22 of absorbent material suitably mounted on a cover plate 23 adapted to be secured to the inclined portion 20 by screws 24 or other suitable means. The pad 22 is intended to be saturated with a suitable neutralizing and deodorizing agent in fluid form, and for supplying fluid to the pad, a conduit or tube 25 is operatively related at one of its ends to the pad 22 through the cover plate 23 adjacent their upper ends and at its opposite end is adapted to communicate with a source of fluid supply indicated, in the present instance, as a receptacle 26 which may be suitably mounted on a convenient part of a vehicle and positioned preferably above the discharge end of the tube 25, from which fluid may be fed by gravity to the pad 22, and by reason of the discharge end of the tube 25 being positioned adjacent the upper end of the pad 22, the fluid deposited in the pad will flow by gravity throughout the length of the pad towards the lower end thereof. If desired, the flow of fluid through the tube 25 may be controlled by any suitable means as, for example, by a valve

27 positioned between the receptacle 26 and the discharge end of the tube.

It will be observed from the foregoing description that as the exhaust gases of combustion are discharged from the muffler 5 through the pipe 8 and the tubular member 9, a vacuum will be created in the space 12 between the periphery of the pipe 8 and the inner face of the tubular member 9, which will serve to draw air through the space or passage 15 of the housing and through the space 12 to be mixed with the gases of combustion, thereby adding to the oxygen content of the gases, and dissipating by dilution, a substantial portion of the carbon monoxide inherent in such gases, while the successive exhaust impulses discharged from the end of the tubular member 9 will draw a portion of the air entering the space 15 across the surface of the pad 22 in a manner to take up and absorb a quantity of the neutralizing and deodorizing fluid with which the pad is saturated and carry it to adjacent the discharge end of the housing where it is mixed with the exhaust gases for neutralizing the gases by chemical action and dissipating the obnoxious odors contained in the products of combustion.

It will be observed also that when the muffler and housing are being moved in a forward direction as by the movement of a vehicle on which they may be mounted, the flared end 18 of the portion 14 of the housing will collect a substantial volume of air to be passed through the spaces 15 and 12 and across the pad 22, thereby providing a pressure to assist the vacuum created by the exhaust impulses for passing the air through the housing with even greater velocity than when the muffler is stationary.

It will be further observed that the present invention provides apparatus for effectually combining the vapors of a neutralizing and deodorizing fluid with the exhaust gases of combustion and the oxygen content of the air taken into the housing through the passage 15, thereby materially diluting the dangerous carbon-monoxide gas and modifying or eliminating obnoxious odors contained in the exhaust gases discharged from the exhaust pipe 8 or other discharge means connected, particularly, with the combustion chamber of internal combustion engines.

Obviously the present invention is not limited to the precise construction and arrangement shown and described, as the same may be variously modified. Moreover, all the features of the invention need not be used conjointly, as the same may be used to advantage in variously different combinations and subcombinations.

What I claim as new and desire to secure by Letters Patent is:

1. In a device of the class described, the combination with a muffler casing having an exhaust pipe operatively related to one of its end portions, of a housing mounted on said casing in spaced relation thereto and having a portion surrounding and spaced from said pipe, said housing being open at its ends and tapered toward its

rear end portion to extend beyond the discharge end of said pipe, and a pad of absorbent material positioned in said housing adjacent the outer end of said pipe.

2. In a device of the class described, the combination with a muffler casing having an exhaust pipe operatively related to one of its end portions, of a tubular member mounted on and surrounding said pipe in spaced relation thereto and extending beyond the end thereof, a housing mounted on said muffler casing in spaced relation thereto and having a portion surrounding and spaced from said tubular member and pipe, said housing being open at its ends and tapered toward its rear end portion to extend beyond the discharge end of said tubular member, a pad of absorbent material positioned in said housing adjacent the end of said pipe, and means for conducting fluid to said pad.

3. In a device of the class described, the combination with a muffler casing having an exhaust pipe operatively related to one of its end portions, of a tubular member surrounding said pipe in spaced relation thereto and extending beyond the discharge end thereof, a housing having one of its ends extending a substantial distance along said muffler casing in spaced relation thereto and having its longitudinal side edges secured to said casing, the opposite end of said housing surrounding said tubular member and pipe and being tapered to provide an inclined portion adjacent the discharge end of said member, and a pad of absorbent material positioned in the inclined portion of said housing.

4. In a device of the class described, the combination with a muffler casing having an exhaust pipe operatively related to one of its end portions, of a tubular member surrounding said pipe in spaced relation thereto and extending beyond the discharge end thereof, a housing having one of its ends extending forwardly a substantial distance along the lower side of said muffler casing in spaced relation thereto and having its upper longitudinal edge portions secured to opposite sides of said casing, the opposite end of said housing surrounding said tubular member and pipe and being tapered to provide an inclined lower portion adjacent the discharge end of said member, a pad of absorbent material removably mounted in the inclined portion of said housing, and means for supplying fluid to said pad.

5. In a device of the class described, the combination with a muffler casing having an exhaust pipe operatively related to one of its end portions, of a housing mounted on said casing in spaced relation thereto and having a portion surrounding and spaced from said pipe, said housing being open at its ends and tapered toward its rear end portion to extend beyond the discharge end of said pipe, and a pad of absorbent material positioned in said housing between the open ends thereof.

MAX H. WOLFF.
